Primary Examiner — Richard Kearney*Assistant Examiner* — Benjamin M Weeks(74) *Attorney, Agent, or Firm* — Thomas B. McGurk(57) **CLAIM**

The ornamental design for an eyeglass holder, as shown and described.

DESCRIPTION

FIG. 1 is a perspective view of an eyeglass holder illustrating the claimed design.

FIG. 2 is a front view of the eyeglass holder shown in FIG. 1.

FIG. 3 is a right side view of the eyeglass holder shown in FIG. 1.

FIG. 4 is a left side view of the eyeglass holder shown in FIG. 1.

FIG. 5 is a bottom view of the eyeglass holder shown in FIG. 1.

FIG. 6 is a top view of the eyeglass holder shown in FIG. 1; and,

FIG. 7 is a rear view of the eyeglass holder shown in FIG. 1.
